UNITED STATES PATENT OFFICE.

RALPH F. DISERENS, OF BRADFORD, PENNSYLVANIA.

NOZZLE FOR PNEUMATIC CARPET-CLEANING APPARATUS.

No. 850,909.

Specification of Letters Patent.

Patented April 23, 1907.

Application filed July 6, 1906. Serial No. 324,733.

To all whom it may concern:

Be it known that I, RALPH F. DISERENS, a citizen of the United States, residing at Bradford, in the county of McKean and State of Pennsylvania, have invented certain new and useful Improvements in Nozzles for Pneumatic Carpet-Cleaning Apparatus, of which the following is a specification.

My invention relates to pneumatic carpet-cleaning apparatus, and more particularly to the dust-collecting nozzles adapted to be brought into contact with the object to be cleaned, and its novelty consists in the construction and adaptation of the parts, as will be more fully hereinafter pointed out.

In the drawings, Figure 1 is a top plan view of a nozzle embodying my invention. Fig. 2 is a side view thereof. Fig. 3 is a central longitudinal section, and Fig. 4 is a bottom plan view.

In the drawings, 10 is a pipe connected at 11 by a coupling to any suitable hose 12, which in turn leads to a vacuum-producing means, as a fan or pump. (Not shown.)

20 20 is a nozzle comprising a throat 21, made up of the side walls 22 22 and the end walls 23 23 and restricted laterally to form a neck 24, which is threaded at 25 to engage with the threaded end of the suction-pipe 10. The 30 neck is bent at 26 to make the device more convenient for the operator to handle and move over the carpet or other surface to be treated. Transversely arranged between the walls 22 22 and 23 23 is a diaphragm 30, perforated at 31 31 to permit of the passage of the air and dust through the same to the throat 21. Beyond this diaphragm is a mouth 40, formed of the jaws 41 41, and within said mouth is an intermediate tongue 42, which extends beyond the plane of the edge of the mouth from the diaphragm 30, which forms the rear wall of said mouth.

In the construction shown the jaws 41 are made integral with the side walls 22 22 and 45 form a continuation thereof, and the tongue 42 is made integral with the diaphragm 30 and is placed substantially at right angles thereto.

The mouth 40 is divided into two compartments 50 43 and 44 by the intermediate tongue

42, and this tongue 42 serves the double function of a scraper against the surface of the carpet or other object to be cleaned and a support which will always keep the edge of one of the jaws 41 out of contact with such surface.

The manner of using the device is as follows: The vacuum-producing means being set in operation, the workman places the nozzle against the carpet in about the manner shown in Figs. 2 and 3, the tongue 42 and one of the jaws 41 resting thereon. The nozzle being then drawn over the carpet, (designated by the numeral 50,) the dust disturbed thereby is rapidly drawn first into the compartments 43 and 44 and thence through the apertures 31 31 into the throat 21, whence it is drawn into the pipe 10 and beyond to the final place of collection and removal.

I have found this device very efficient in practice. The tongue 42 seems to open the pile or nap of the fabric and disturb the dust in and under the carpet and to facilitate its removal, and the division thereby of the mouth into two relatively narrow compartments 43 and 44 subjects each part of the carpet to the action of the two currents of air first through one compartment and then the other, and as these two compartments are completely separated from each other and have their mouths located in different planes each part of the fabric will by reason of this double action be effectually cleaned, while the removal of the throat an appreciable distance away from the carpet seems to more effectually take away the dust from its surface.

What I claim as new is—

1. A nozzle for a pneumatic carpet-cleaner, having within its interior an apertured diaphragm arranged rearward of its mouth, and provided with a tongue which divides the nozzle into a plurality of compartments and extends from said diaphragm to a plane outside said mouth.

2. A nozzle for a pneumatic carpet-cleaner, having within its interior an apertured diaphragm, jaws extending forward of said diaphragm and forming a mouth in front of the latter, and a tongue which divides the mouth into a plurality of compartments and ex-

2
tends from said diaphragm to a plane outside said mouth, said parts relatively arranged so that the edges of the jaws of one compartment will be in a different plane than those of the other.

3. A nozzle for a pneumatic carpet-cleaner, having within its interior an apertured diaphragm, jaws extending forward of said diaphragm and forming a mouth in front of the

latter, and a tongue extending across said mouth and forward of the jaws.

In testimony whereof I affix my signature in presence of two witnesses.

RALPH F. DISERENS.
